CLAIM

The ornamental design for a switch cover, as shown and described.

DESCRIPTION

FIG. 1 is a front view of the switch cover showing my new design;

FIG. 2 is a left-side view thereof;

FIG. 3 is a right-side view thereof;

FIG. 4 is a top view thereof;

FIG. 5 is a bottom view thereof;

FIG. 6 is a top, right-side, and front perspective view thereof; and,

FIG. 7 is a top, left-side, and front perspective view thereof. The rear view of the switch cover is a mirror image of the front view thereof.

1 Claim, 3 Drawing Sheets
